SLUG CASTING MACHINE

Luther E. Morrison, New York, N. Y., assignor to
 Mergenthaler Linotype Company, a corpora-
 tion of New York

Application March 7, 1932. Serial No. 597,192

15 Claims. (Cl. 199—60)

This invention relates to slug casting machines, wherein printing slugs or type bars are cast in a slotted mold and delivered by an ejector advancing from the rear against the edge of the slug. In these machines, the molds are adjustable in length to produce slugs of different lengths, as for printing columns or pages of different width, and the ejector employed is therefore constructed so that it may be varied in width to correspond 10 with changes in the length of the mold slot.

For instance, as illustrated in U. S. Letters Patent to John R. Rogers, No. 967,976, there is commonly employed a composite ejector comprising a series of blades arranged edge to edge in 15 contacting relation, and suitable devices whereby any desired number of blades can be connected with the ejector slide while the others are left free and remain at rest. These ejector blades are quite thin, being made so to serve for the 20 ejection of very thin slugs, as well as of the thicker slugs.

In recent years, there has been a growing tendency to increase the thickness of the printing slugs and to such extent that the ejector above 25 described is sometimes found to be incapable of ejecting the slugs from the molds in a thoroughly satisfactory manner. Thus, it frequently happens that the ejector, because of its thinness, will embed itself in the bottom edges of the slugs 30 and fail to eject them fully from the mold, or that, because of undue resistance offered by the slugs, the ejector blades or other parts of the machine will be damaged in the act of ejection. These objections arise particularly with the larger 35 or thicker slugs, which are of the ribbed variety, i. e., comprise a solid body portion, an overhanging type-carrying portion, and a series of ribs cast on the body portion and giving support to the overhanging portion.

40 In the ejection of such ribbed slugs, the ejector is arranged to engage only with the solid body portion, and since such portion is located well to one side of the central plane of the slugs, the latter have a tendency to cant or tilt in the mold 45 and thereby offer greater resistance to ejection than in the case of thinner slugs whose body portions are located close to or in the central plane.

The present invention is intended to overcome 50 these and other objections and contemplates an ejector which may not only be adjusted in width, but which may be adjusted in thickness as well, so as to be capable of cooperating with slugs of all dimensions, whether long or short or thick or 55 thin. In the specific embodiment illustrated, the

ejector proper comprises two distinct ejector sections arranged side by side and mounted in a support or carrier which is capable of lateral adjustment to bring either section into operative position for independent use. Each section is 60 made up of a set of ejector blades, those of one set having a certain predetermined thickness and disposed vertically edge to edge in contacting relation, while those of the other set, although similarly disposed, include blades formed with 65 horizontal ribs or flanges which give to that particular section a greater effective thickness. The ejector or actuating slide (before mentioned) is common to both sections and may be operatively connected to either section to the exclusion of 70 the other.

When casting thin slugs, the ejector section comprising the thinner blades is used since they are capable of ejecting such thin slugs; whereas, when casting thicker slugs (usually of the ribbed 75 variety), the other section having the flanged blades is used, the vertically disposed portions of these blades being arranged to engage the slugs by their relatively narrow bodies, and the horizontally disposed flange portions thereof being 80 arranged to engage the slugs by their reinforcing ribs. In this way, as will be readily apparent, the effective thickness of the ejector proper may be changed at will to correspond to the thickness of the slugs being cast.

85 Provision is also made for varying the width of either section of the improved ejector to correspond to the varying lengths of the slugs to be cast. This is accomplished by connecting any selected number of blades of the active section 90 or set to the actuating slide, the selection of blades being controlled by means of a vertically adjustable bar which can be set in different vertical positions by the operation of a hand lever arranged conveniently at the front of the ma- 95

In the accompanying drawings, the invention has been shown merely in preferred form and by way of example, and obviously many changes and modifications may be made therein and in 100 its mode of application without departing from the spirit of the invention. It should be understood, therefore, that the invention is not limited to any specific form or embodiment except insofar as such limitations are specified in the ap- 105 pended claims.

Referring to the drawings:

Fig. 1 is a side elevation partly broken away 110 of an ejecting mechanism constructed in accordance with the invention;

Fig. 2 is a similar view on a slightly enlarged scale showing further details of construction;

Fig. 3 is a front elevation, partly broken away, of the parts shown in Fig. 1;

5 Fig. 4 is a longitudinal section taken on the line 4—4 of Fig. 2 showing the ejector or actuating slide in its normal or retracted position and the ribbed section of the ejector proper in use;

10 Fig. 5 is a detail perspective view showing the connections between the individual ejector blades and their respective slide rods;

15 Fig. 6 is a view similar to Fig. 4, but showing the actuating slide in its forward position and the plain section of the ejector proper in use;

20 Fig. 7 is a vertical section taken on the line 7—7 of Fig. 4; and

25 Fig. 8 is a vertical section taken on the line 8—8 of Fig. 6.

The mold wheel A is provided with two or more 30 slug casting molds A¹, A², which are adjustable both as to length and width of the mold slot or cavity. Ordinarily, four molds of different sizes are mounted on the wheel, and the latter is manually adjusted to bring any selected mold 35 into use. The mold A¹ (Fig. 6) is representative of the kind used for casting the thin slugs, while the mold A² (Fig. 4) is representative of the kind used for casting the thicker slugs. The thin slugs are usually of the plain or solid variety, whereas the thicker slugs are usually of the ribbed or 40 recessed variety as shown in Fig. 2, where it will be seen that the ribbed slug therein illustrated comprises a solid body portion 1, an overhanging type-carrying portion 2, and a series of ribs 3 cast on the side of the body portion and giving support to the overhanging portion. The mold A² for casting such a ribbed slug is of course shaped or fashioned to correspond, it being sufficient to say that the ribs 3 are cast in fore-and-aft grooves formed in the cap portion of the mold. If any further information is desired as to the 45 form or construction of the mold and slugs, reference may be had to the Hall Patent, No. 665,212.

The mold wheel A (see Fig. 3) is mounted for 50 rotation upon the lateral arm A³ of a fore-and-aft mold slide A⁴, which latter is moved forwardly and backwardly in suitable guideways to carry the active mold, first (i. e., at the time of casting) into and out of contact with the composed matrix line, and later (i. e., at the time of ejection) into and out of operative relation to the trimming knives, all in the usual way.

Coming now to the present invention, the improved ejecting mechanism includes as usual a 55 fore-and-aft actuating slide B mounted for reciprocation in the mold slide A⁴ and operated in the regular way through a connecting link B¹ from the main drive shaft of the machine. The ejector proper comprises two distinct sections C and D arranged side by side and supported in a suitable frame or carrier E which is adjustable laterally in opposite directions to bring one section or the other into operative position.

The ejector section C is made up of a set of 60 blades C¹ arranged edge to edge in the regular way so as to produce collectively a composite blade of a given uniform thickness and capable of ejecting the thin unrecessed slugs from the molds A¹; whereas, the ejector section D is made up of a set of blades D¹, D², which differ in 65 form so as to produce a composite blade of a greater effective thickness and capable of ejecting thicker slugs of the recessed variety from the molds A². The blades D¹ of the section D are 70 identical with the blades C¹ of the section C,

while the blades D² thereof are formed with lateral ribs or flanges d of a predetermined width.

As shown in Figs. 7 and 8, the blades D¹ and D² are disposed alternately one above the other and the flanges d are spaced apart so as to agree with the spacing of the slug ribs 3. The purchase of the section D upon a slug at the time of ejection will, therefore, be distributed on both sides of its central plane, the vertical portions of the blades D² and the intermediate blades D¹ being 80 adapted to engage the body portions 1 of the slug, and the flanges d to engage the ribbed portions 3 thereof. Possible damage to the ejecting mechanism is thus averted and a perfect delivery 85 of the slug is assured.

90 The frame E (see Fig. 2) is slidably mounted in a pocket or recess A⁵ formed in the mold slide A⁴ and guided in its movement by means of tongue and groove connections E¹. The movement of the frame E in one direction (toward the left, according to Figs. 7 and 8) is opposed by a pair of compression springs A⁶ seated in corresponding recesses A⁷ formed in the mold slide, and tending to move the frame in the opposite direction into engagement with a pair of stop or 95 retaining screws A⁸.

In the present embodiment illustrated, the adjustment of the frame E is effected by the manual operation of a crank arm O, which may be set in different positions according to the ejector 100 section to be selected. The crank arm O (best shown in Fig. 3) is attached to the front end of a short rock shaft O¹ and provided with a spring latch O² controlled by a finger button O⁴ and arranged to cooperate with a pair of notches 105 p¹, p², formed in a fixed segmental plate P. At its rear end (see Fig. 1), the rock shaft O¹ is provided with an upright arm O³ which is loosely connected to the frame E through the medium of a cross pin e, the latter being anchored between a pair of lugs e¹ projecting from the contiguous side face of the frame. The space allowed between the lugs e¹ permits the reciprocation of the mold slide to take place in the 110 regular way during the casting and ejecting periods without interfering with the arm O³.

According to the above arrangement, when the crank arm O by means of the button O³ is 115 swung to the position shown by the full lines in Fig. 3, the frame E will be pushed inwardly by the arm O³ and, as the latch O² is allowed to engage the notch p¹, the ejector section D will be locked in operative position (see Figs. 4 and 7). Conversely, when the crank arm O is swung to the position indicated by the dotted lines in Fig. 130 3, the frame E will be pushed outwardly by the springs A⁶ into engagement with the banking screws A⁸ and, as the latch O² is allowed to engage the notch p², the ejector section C will be locked in operative position (see Figs. 6 and 8). 135

The ejector sections C and D are actuated by the ejector slide B through the medium of a single set of fore-and-aft slide rods F and a vertical adjustable bar G arranged to engage rectangular lugs f formed on the rear ends of the 140 said rods. As the section C or the section D is brought into active position, connections between the individual blades thereof and the slide rods F are established by means of upstanding lugs f¹ formed on the front ends of the said rods and corresponding notches c¹ or d¹, formed in the rear ends of the blades C¹ or D¹ and D² (see Figs. 2 and 5). The slide rods F are mounted and guided as usual in longitudinal grooves c¹ formed 145 in the mold slide A⁴ and, during the reciprocation 150

of the ejector slide B, are adapted to obtain similar support in the frame E, the latter for this purpose (see Figs. 7 and 8) being formed with two series of superposed slots E² and E³ which extend through the frame from front to rear and are brought into registry with the slides under the different adjustments of the frame. The blades C¹, as well as the blades D¹ and D², are reduced in width at their rear ends adjoining the notches c¹ and d¹ (see Fig. 5) so as to clear the rods F as the frame E is adjusted laterally.

The construction of the ejector or actuating slide B, the bar G, and the means provided for adjusting said bar, are similar in all respects to the corresponding mechanism used in the commercial linotype machines or as illustrated in the Rogers Patent No. 987,976, before referred to. Thus, the bar G is mounted as usual to slide vertically in a grooved guideway b formed in the actuating slide B, the opposite edges of the groove snugly engaging the opposite edges of the bar so that the latter is caused to move forwardly and backwardly with the actuating slide. At its lower end, the bar G is slidably supported upon a long fore-and-aft rod G¹ carried by a vertically adjustable slide G², which is operable by a hand lever G³ extended to the front of the machine.

By means of this arrangement, the bar G may be set in different positions to connect the actuating slide B with any desired number of the blades in either the ejector section C or the ejector section D, according to the adjusted position of the frame E or according to which section happens to be in use at the time. For example, the member G, as shown in Fig. 2, is set to connect twelve blades (counting from the bottom) of the ejector section D with the actuating slide B, leaving the two uppermost blades free or disconnected from the slide. Consequently, when the slide B is moved forward to expel the cast slug from the mold, the bar G is moved with it, its forward edge engaging the lugs f on the rear ends of the appropriate slides F, which are thus pushed forwardly and through the lugs f¹ actuate the selected ejector blades D¹ and D² (see Figs. 4 and 5). During the return stroke of the actuating slide B, a rib or shoulder b¹ formed thereon, and located in advance of the lugs f, engages the latter and by such engagement draws back the slides F and the connected blades D¹ and D².

When the section C is in use, the blades C¹ are selected and operated in the regular way or as set forth in the aforementioned Rogers patent.

From the foregoing description, it will be seen that the improved ejecting mechanism includes an ejector proper comprising two composite interchangeable ejector sections of different effective thicknesses, either of which may be selected at will, altered in width and operatively connected to the common actuating slide B. Furthermore, variations in width of the ejector sections C and D are effected by means also common to both sections, including the selecting bar G, the hand lever G³, and the intermediate connecting devices before described.

Having thus described my invention, what I claim is:

1. In or for a slug casting machine, a slug ejecting mechanism having an ejector proper comprising two distinct ejector sections of different effective thicknesses, each of said sections being variable in width and usable independently of the other section.

2. In or for a slug casting machine, a slug ejecting mechanism having an ejector proper com-

prising two distinct ejector sections variable in width, and means for selecting either section for independent use.

3. In or for a slug casting machine, a slug ejecting mechanism having an ejector proper comprising two distinct ejector sections variable in width, a movable support for both sections, and means for adjusting the support to bring either section into use, as desired.

4. A slug ejecting mechanism as specified in claim 2 characterized by the fact that the individual sections of the ejector proper are made up of a series of ejector blades.

5. In or for a slug casting machine, a slug ejecting mechanism having an ejector proper comprising two composite ejector sections variable in width, an actuating slide common to both sections, and means for connecting either section to the actuating slide, as desired.

6. In or for a slug casting machine, a slug ejecting mechanism having an ejector proper comprising two distinct ejector sections, one section being of a given uniform thickness, and the other section being formed with projecting ribs or flanges to give it a greater effective thickness, each section being usable independently of the other section and variable in width when in use.

7. A slug ejecting mechanism as specified in claim 6 characterized by the fact that each ejector section is made up of a series of blades and that the said projecting flanges are formed on certain selected blades of one series.

8. In or for a slug casting machine, a slug ejecting mechanism having an ejector proper comprising two composite ejector sections of different thicknesses, means operable at will for selecting either section for independent use, and means for varying the effective width of the selected section.

9. In or for a slug casting machine, a slug ejecting mechanism having two distinct sets of ejector blades, means for selecting either set for independent use, an actuating slide common to both sets, and means for connecting different selected numbers of blades of the active set to the actuating slide.

10. In or for a slug casting machine, a slug ejecting mechanism having an ejector proper comprising two distinct ejector sections of different effective thicknesses and adjustable in width, means for selecting either section for independent use, and unitary means for effecting the adjustments in width of the active section.

11. In or for a slug casting machine, a slug ejecting mechanism having an ejector proper comprising two composite ejector sections, and unitary means operable at will for varying the effective width of both sections.

12. A slug ejecting mechanism as specified in claim 10 including an actuating slide common to both ejector sections and characterized by the fact that the said adjusting means is also common to both ejector sections.

13. In or for a slug casting machine, a slug ejecting mechanism having an ejector proper comprising two distinct ejector sections arranged side by side, one section being made up of a series of blades of a given thickness and disposed vertically edge to edge in contacting relation, and the other section being made up of a series of similarly disposed blades, certain of which are formed with horizontally disposed ribs or flanges to give them a greater effective thickness, means for selecting either section for independent use,

and means for varying the effective width of the active section.

14. In or for a slug casting machine, a slug ejecting mechanism having an ejector proper comprising two distinct sets of ejector blades arranged side by side, a movable support for both sets, means for adjusting the support to bring either set into the operative position, a common actuating slide, and means for connecting dif-

ferent selected numbers of blades of the active set to said slide.

15. A slug ejecting mechanism as specified in claim 14 characterized by the fact that the blades of one of the sets therein referred to are of a given thickness and that certain blades of the other set are of a greater effective thickness.
